UNITED STATES PATENT OFFICE.

LAVERR CLEVELAND, OF MANSFIELD, OHIO.

GLOVE.

Application filed December 26, 1919. Serial No. 347,285.

To all whom it may concern:

Be it known that I, LAVERR CLEVELAND, of Mansfield, Ohio, have invented certain new and useful Improvements in Gloves, and do hereby declare that the following is a full, clear, and exact description thereof.

My invention relates to gloves, or other hand coverings, and more particularly to gloves made of woven fabric, such as canvas, 10 and my object is to greatly increase their wearing properties with practically no increase in cost of manufacture, and to this end my invention consists in the glove, or other hand covering constructed substantially as hereinafter specified and described 15 by or comprised within the language or meaning of the claims.

In the accompanying drawing:

Fig. 1 is a view, in elevation, of a glove, 20 embodying my invention, showing the palm side;

Fig. 2 is a like view with the glove turned inside out;

Fig. 3 is a longitudinal section on the line 25 3—3 of Fig. 1;

Fig. 4 is a cross section on the line 4—4 of Fig. 1.

The type or kind of glove which I show in the drawing is one in which palm and back are of canvas, cut to conform to the 30 contour of the hand and fingers and stitched together along the edges, and joined to a knitted wristband. The great wear in this class of glove falls on the palm, or inner 35 side thereof, and not on the back, so that the life of the glove is limited to the wearing qualities of the palm. Obviously, prolongation of the life of the palm, if it can be done at but little or no great cost, and without 40 causing any discomfort to the wearer, is a very desirable thing, and by my invention I accomplish all this.

In carrying my invention into practice, I make a back 10 of a single thickness or ply 45 of cloth, or fabric, as usual, and the palm

(including the four fingers and thumb) of two thicknesses or plies, an outer ply 11 and an inner ply 12, these two being duplicates, and in contour matching the back, and I quilt these two plies, or join them at close 50 intervals, by lines 13 of stitching that preferably extend only longitudinally of the glove, and clear across the fingers. By thus joining the two plies to one another they lie compactly together, and, hence, no objectionable bulk or thickness of material exists 55 to cause discomfort to the wearer and diminish the flexibility of the palm portion of the glove, which should be of high flexibility, and no buckling or bulging of one ply 60 from another can occur in doubling or closing up the hand in grasping. The added cost of manufacture is merely the second ply material and the trifling expense of stitching the two plies together. In all other 65 respects my glove involves nothing more in its manufacture, than the ordinary single ply back and palm glove.

I claim:

1. A hand covering comprising single 70 ply back and plural ply palm members and all plies being of cloth, the cloth of the palm plies being continuous over the entire palm area and the palm plies being joined by lines of stitches that extend only longitudinally of the hand covering and spaced apart transversely thereof throughout their longitudinal extent.

2. A glove having a single ply back and a double ply palm, the palm plies being joined 80 by lines of stitches that extend only longitudinally of the glove and crossing the fingers lengthwise thereof, said lines of stitches being spaced apart throughout their longitudinal extent, and all plies being of cloth, 85 the cloth of the palm plies being continuous over the entire palm area.

In testimony that I claim the foregoing, I have hereunto set my hand.

LAVERR CLEVELAND.
